UNITED STATES PATENT OFFICE

GROVER C. LEE, OF TAFT, CALIFORNIA

OIL BURNER

Application filed June 1, 1928. Serial No. 282,194.

This invention has for its object the provision of a cheap device whereby crude oil or distillate may be efficiently utilized as a fuel. The invention provides a device which may be employed within the fire-box of an ordinary stove or in any manner external to a stove and without occupying a great deal of space will furnish a relatively large volume of heat for cooking or heating. 10 The invention is illustrated in the accompanying drawing and will be hereinafter fully set forth.

In the drawing:

Figure 1 is a vertical section illustrating 15 the burner mounted within the fire-box of a stove, and

Fig. 2 is a perspective view of the burner removed.

Referring more particularly to Fig. 1, the 20 numeral 1 indicates the top and the numeral 2 the front of a fire-box of a stove which may have any desired form. For the most efficient use of my improved burner, a draft pipe 3 is fitted in the front of the fire-box 25 and extends inwardly and somewhat downwardly therefrom, while a fuel supply pipe 4 is secured in and extends through the top of the fire-box and has its lower end disposed within a nipple 5, said nipple being 30 in turn threaded through a boss 6 provided therefor on the top 7 of the burner. The burner may be formed of any suitable material and may be a casting or heavy gage sheet metal pressed or folded into the desired form, but, however it may be produced, it presents a hollow or tubular body 8 which will preferably be disposed in an inclined position, as shown in Fig. 1 of the drawing, and tapers towards its upper end. 40 At said upper end, a deflecting spreader 9 is provided, said spreader consisting of a plate extending laterally from each side of the body and doubled or rolled on itself to provide an upper leaf 10, the edge of which 45 is spaced from the upper end of the top of

the burner body. At its lower end, the bottom wall 11 of the burner body is carried downwardly beyond the plane of the greater portion of the bottom or back of the body and is then carried forwardly and upwardly, 50 as shown at 12, whereby the lower end of the tubular body is formed into a cup or reservoir 13, the fuel supply pipe 4 being located approximately over this reservoir and the upper portion of the reservoir being 55 open, as indicated at 14, whereby the end of the draft pipe 3 may be so disposed as to direct inflowing air into the interior of the burner body. The draft pipe may be utilized to partly support the burner, any convenient brackets or other fastenings being 60 provided to furnish needed additional supports and secure the burner in its proper position.

In use, a small quantity of kerosene or 65 some other easily ignited oil is placed in the reservoir or cup 13 and is ignited by the use of a match or other lighter. The burning of this oil will heat the walls of the burner body so that the bottom or lower 70 portion thereof will become highly heated and serve as a vaporizing plate. When the consumption of this preliminary charge of oil has been completed, the fuel oil is permitted to flow to the burner through the 75 supply pipe 4, it being understood that the fuel is fed from a supply tank or reservoir located at a proper distance from the burner for safety and fitted with a cut-off valve so that the flow of the fuel may be set up 80 whenever desired and may be easily regulated. The inflowing fuel should be so restricted that it will emerge from the supply pipe in drops which will fall at once onto the heated bottom or vaporizing plate 85 of the burner body so that it will be at once ignited, and the draft pipe 3 will admit sufficient air to mingle with the fuel and form a proper combustible mixture. Moreover, the air flowing in through the draft 90

pipe 3 will naturally flow up through the tapered tubular burner body and impinge against the deflecting spreader 9 so that it will be turned laterally to both sides of the burner. The flame caused by the ignition of the fuel will, of course, follow the inflowing air and it, too, will be spread at the upper end of the burner body by the U-shaped or grooved deflector, the upwardly 10 tapered tubular body aiding in forming the proper draft, and the leaf 10 will turn the flame back upon the body and maintain that temperature thereof which will make for proper vaporization and combustion. While the fuel should be admitted in drops, the flow of the successive drops should be sufficiently rapid to maintain a substantially constant feed of fuel to the vaporizing plate so that there will be a 15 constant steady flame flowing upwardly through the burner body and turned aside at the upper end thereof and heat will be distributed throughout the fire-box of the stove or spread in all directions if the burner 20 should be used in the open. The device is exceedingly simple in its construction and may be produced at a very low cost, and I have found by actual test that it operates in a highly efficient manner.

Having thus described the invention, I 30 claim:

1. An oil burner comprising an inclined hollow upwardly tapered open-ended body, a lateral deflecting flame spreader across the 35 upper smaller end of the body, the bottom wall of the body constituting a vaporizing plate at its lower larger end, and with a fuel inlet through the top of the body adjacent the larger end thereof.

2. An oil burner comprising a hollow upwardly tapered inclined body having its lower wall at its larger end turned up to form a reservoir having an open top, an air draft pipe leading into said open top, a lateral deflecting flame spreader extending 45 across the upper end of the burner body, and means in the top of the body adjacent the air draft pipe and said reservoir for admitting fuel thereto.

3. An oil burner comprising a hollow inclined upwardly tapered open-ended body provided at its upper end with a flame spreader consisting of a plate extending laterally from each side of the burner body 55 and having an overhanging leaf extending from end to end thereof and directed toward and spaced from the end of the burner body.

4. An oil burner comprising an inclined upwardly tapered tubular body having its 60 bottom wall turned upwardly at its lower end to form an integral oil-holding cup, the upper end of the body being open and an air inlet being provided in the upper wall of the body at the lower end thereof 65 adjacent and above the oil cup, means for

delivering oil into the oil cup, and a flame spreader consisting of a plate doubled longitudinally upon itself from end to end and forming a lower leaf integral with the lower wall of the body at the upper end thereof 70 and extending laterally from the opposite sides thereof and an upper leaf parallel with the lower leaf and having its edge spaced from the open upper end of the body.

In testimony whereof I affix my signature. 75
